UNITED STATES PATENT OFFICE.

RALPH W. BORCHERT, OF ST. LOUIS, MISSOURI.

MARINE-MOTOR ATTACHMENT.

1,328,313.

Specification of Letters Patent. Patented Jan. 20, 1920.

Application filed June 2, 1919. Serial No. 301,193.

To all whom it may concern:

Be it known that I, RALPH W. BORCHERT, a citizen of the United States, residing at the city of St. Louis and State of Missouri, have invented a new and useful Marine-Motor Attachment, of which the following is a specification.

This invention relates to marine motor attachments.

10. My invention is particularly adapted to support a motor in connection with the stern of a boat in a manner permitting the propeller to be raised above the water to enable the motor to be started more rapidly 15 and easily than could be done if the motor remained in the water.

My invention also includes a novel construction by which the propeller can be supported out of the water when desired, as 20 when the boat is landing or passing over shoals or other submerged objects.

25 The invention also includes novel means by which the propeller shaft can be held in vertical adjustment irrespective of the shape or angle of inclination of the stern board of the boat.

An object of the invention is to provide an improved motor attachment for serving the functions above stated and others hereinafter mentioned.

30 Other objects of the invention will appear from the following description in which reference is made to the drawing illustrating the invention, and in which—

35. Figure 1 is a side elevation of my improved motor attachment.

Fig. 2 is a view looking toward the other side from that shown in Fig. 1.

40. Fig. 3 is a detailed view illustrating the means by which the propeller is supported in any desired adjustment.

Figs. 4 and 5 are detailed views illustrating the heating device for heating the gasoline passing to the motor.

45. Fig. 6 is a detailed sectional view showing the switch device controlling the circuit of the ignition system of the engine.

The invention shown in Figs. 1 to 5 comprises means for supporting the motor in 50 a manner to permit the propeller to be raised manually out of the water for any desired purpose, and also to permit the propeller to be raised, without injury thereto, by contact of the motor support with any 55 submerged object, or when the motor is pass-

ing over shoals. As shown, the motor is pivotally supported by a bracket 1 adapted to engage the stern board of a boat, and equipped with a clamp device 2 for preventing dislodgment of the bracket. From 60 the motor a sleeve 3 extends, inclosing the usual propeller shaft 4.

An arcuate member comprising two arms 5 is attached to the bracket 1. The center of curvature of the arms 5 is the axis of 65 the pivot 6 supporting the motor in connection with the bracket 1.

The upper edge of each arm of the member 5 is provided with ratchet teeth, as shown. A bracket comprising a collar 7 and a frame 8 is attached to the sleeve 3. A pawl 9 is pivotally supported within the frame 8 and is actuated downwardly into engagement with the ratchet teeth on the arms 5 by a spring 10. Thus the motor 75 shaft may be supported vertically, irrespective of the angle of inclination of the stern board of the boat. Furthermore, this construction permits the propeller to be raised entirely above the water which is a matter 80 of considerable convenience in starting the motor, particularly in cold weather. After the motor has been started and the engine has become heated, the propeller may be easily dropped into the water by proper control of the pawl 9 which may be engaged with the members 5 at the proper place to hold the propeller shaft in vertical position.

85. The construction is also of advantage because it permits the propeller to be lifted quickly, either by hand or automatically, out of the water when passing over shoals, or over submerged objects by which the motor might be injured. The construction described also permits the propeller to be supported out of the water when the boat is being towed, thus avoiding the resistance of the water against the propeller.

90. In addition to the advantages mentioned it will be observed by reference to Figs. 1 and 2, that the engine is supported farther astern and does not project, so far over the boat as is the case with the motor attachments now in use.

95. Each of the arms 5 is formed with a slot 11 through which a bolt 12 extends, the said bolt being provided on each end with a thumb nut 13 by which the bolt may be held in any desired position in which it is placed.

100

110

Said bolt is on the forward side of the propeller shaft sleeve 3 and serves as an abutment for said sleeve to support said sleeve in any adjustment in which it may be placed.

5 Thus, said abutment will hold the propeller shaft in proper position, even though the pawl 9 might become disengaged from the ratchet teeth on the arms 5.

As shown in Fig. 2, my invention comprises means for opening the electric circuit as an incident to raising the propeller whether by contact with any submerged object or manually. At this point attention is called to the fact that the arrangement is such that if the propeller support contacts with any submerged object the propeller will be raised thereby, this movement being permitted by the construction described, in which the pawl 9 is free to slide or escape 10 in one direction over the teeth on the arms 5. This prevents any damage or injury to the propeller or to the other motor mechanism. An electric switch 14 in the circuit to the ignition devices of the motor is of the well known type in which there is a push button 15 which is pressed inwardly in the usual manner to close the switch. The well known switch device shown comprises a contact member 15^a in circuit with one of the 15 wires 14^a, and a co-operating member 15^b in circuit with the other wire 14^b. The contact member 15^b is in the form of a spring plate, the resiliency of which is exerted to move the plate 15^b out of contact with the plate 15^a to open the circuit. When the push-button 15 is pressed inwardly, the contact member 15^b is pressed into contact with the contact member 15^a to close the circuit. A cam disk 16 is attached to the pivot 6 supporting 20 the motor. A wide portion of the cam disk is normally in contact with the push button 15 and holds the push button pressed inwardly to close the switch of the circuit. However, when the propeller is raised the 25 push button 15 enters a notch 17 in the disk, leaving the switch free to open in the usual manner. As a result of this operation the motor is stopped as an incident to raising the propeller by contact with any submerged object, or otherwise. However, if the propeller be raised entirely out of the water the disk 16 again closes the switch, thereby closing the electric circuit and leaving the motor 30 free to operate. This is a great convenience in starting the motor, since it permits the propeller to be raised entirely out of the water, thus avoiding the resistance of the water in the initial operation of starting the motor.

35 The invention shown in Figs. 1 and 2 also comprises means for heating the fuel passing to the motor. The heating device comprises a chamber 18 inclosing a number of coils 19 in the passage which conducts the fuel from the fuel tank 20 to the motor. A

burner 21 in the chamber 18 heats the coils 19 so that the fuel passing to the engine is prime and heated.

What I claim is:

1. A device of the character described, comprising a bracket, a motor pivotally supported by said bracket, a switch for controlling the operation of the motor, a propeller supported and driven by the motor, means for supporting the motor and thereby the propeller in different adjustments upon the pivot, and means in connection with the pivot to prevent said switch from opening in one position of the motor and propeller and to permit said switch to open in another position of the motor and propeller. 70

2. A device of the character described comprising a support, a pivot supported by the support, a motor carried by said pivot, a switch controlling the operation of the motor, means for holding the motor on said pivot in different positions relative to said support, and means to prevent the said switch from opening in one position of the motor and to permit the said switch to open 80 in another position of the motor.

3. The combination with a motor, of a bracket, a pivot connecting the bracket and the motor; an arcuate arm having its center of curvature at the axis of the pivot, ratchet teeth on said arm, a sleeve attached to the motor, and a pawl carried by said sleeve for engaging the ratchet teeth. 95

4. The combination with a motor, of a bracket for supporting the motor, a pivot connecting the motor and the bracket, a sleeve in connection with the motor, a pair of curved arms extending on opposite sides of said sleeve, a pawl carried by said sleeve, teeth on said arms adapted to be engaged by 100 said pawl, and an abutment device supported by said arms for said sleeve.

5. The combination with a motor, of a bracket, a pivot connecting the motor and the bracket, an arm attached to said bracket, 110 a sleeve in connection with the motor, a collar on said sleeve, a pawl pivotally supported by said collar and movable into and out of engagement with said arm, and a spring for engaging said pawl with said arm. 115

6. The combination with a motor, of a bracket, a pivot connecting the motor and the bracket, an arm attached to said bracket, a sleeve in connection with the motor, a 120 collar on said sleeve, a pawl pivotally supported by said collar and movable into and out of engagement with said arm, a spring for engaging said pawl with said arm, and an adjustable abutment carried by said arm 125 for holding said sleeve in different adjustments.

7. The combination with a pivotally mounted motor having an ignition system and being movable from a position in which 130

it is desired that the motor be operative to a position in which it is desired that the motor be inoperative, and an electric switch device controlling the ignition system of the motor, of means arranged to close said switch device as an incident to movement of the motor to position in which it is desired that the motor be operative.

8. The combination with a pivotally mounted motor having an ignition system and being movable from a position in which it is desired that the motor be operative to a position in which it is desired that the motor be inoperative, and an electric switch device controlling the ignition system of the motor, of means for closing said switch device as an incident to movement of the motor to position in which it is desired that the motor be operative, and permitting said switch device to open as an incident to movement of said motor to position in which it is desired that the motor remain inoperative.

9. The combination with a pivotally mounted motor movable from a position in

which it is desired that the motor be operative to a position in which it is desired that the motor be inoperative, an electric circuit controlling the operation of the motor, and a switch for opening and closing said circuit, of a device for closing said switch as an incident to movement of the motor to position in which it is desired that the motor be operative.

10. The combination with a pivotally mounted motor movable from a position in which it is desired that the motor be operative to a position in which it is desired that the motor be inoperative, and a device controlling the operation of the motor, of means for moving said device to position to cause the motor to operate as an incident to movement of the motor to position in which it is desired that the motor be operative and permitting said device to move to position to prevent operation of the motor as an incident to movement of the motor to position in which it is desired that the motor be inoperative.

RALPH W. BORCHERT.
